HAIR ROLL OR THE LIKE

William Huppert, New York, N. Y., assignor to
Delamere Company, Inc., a corporation of Del-
aware

Application September 28, 1937, Serial No. 166,038

3 Claims. (Cl. 132—38)

This invention relates to hair rolls or like articles which are used to wind and support hair in the form of a roll, puff, or curl.

Among the objects of the invention are to provide a device of this character for forming the hair in a roll at the back, sides, or other parts of the wearer's head, and for supporting the rolled hair in proper shape and position.

Other objects of the invention are to provide a hair roll which is light in weight, of flexible construction, and easily manipulated.

The invention provides a device of light weight whereby the hair may be wound into a roll of relatively large diameter, which device may be comfortably worn in the hair to support the roll.

The novel features and advantages of my invention will appear more fully from the following description thereof, reference being had to the accompanying drawing, in which:

20 Figure 1 is a side elevation of the device;

Fig. 2 is a similar view with the core member in cross-section as on the line 2—2 of Fig. 3;

Fig. 3 is a cross-sectional view taken on the line 3—3 of Fig. 1, but on a larger scale;

25 Fig. 4 is a view showing the ends of the hair engaged in the device prior to rolling; and

Fig. 5 is a perspective view of a hair roll supported by the device at the back of the wearer's head.

30 The device comprises a tubular core member 10, of braided flexible resilient material, such as horsehair, artificial horsehair, or the like, having sufficient body and stiffness to hold its shape but without undesired rigidity. The core prefer-

35 ably tapers towards its ends, and it is permanently fastened at or adjacent its ends by clasps 12 or other suitable fastening means to a flexible strand or arm 11 that extends lengthwise through the core. The strand 11 may consist of flexible

40 covered wire and forms a part of the member 13. The member 13 is preferably, though not necessarily, formed of a single length of wire in which case its ends may be joined together, preferably within the core, by a clasp 14, or in any other

45 desired manner.

15 is a companion flexible strand or arm extending lengthwise of the core 10 and lying against its outer surface. The strands or arms 13 and 15 may be connected at their outer extremities by U-shaped bends 16.

It should be noted that since the core is permanently fastened at its ends to the strand 13,

the core cannot expand or contract lengthwise although it may be deformed circumferentially by external finger pressure. Upon release of such pressure, however, the core will spring back to its normal shape. This feature, as will be herein-after pointed out, permits of initially gripping the hair ends between the strands 13 and 15 prior to rolling the hair. Furthermore, the core, without materially increasing the weight of the device, provides a form of relatively large diameter 16 around which the hair may be wound into a roll with a few turns of the device.

In using the device, the strand 15 is separated slightly from the core 10 to provide a space therebetween in which the ends of the hair may be inserted, as indicated in Fig. 4. The wire strands 13 and 15 may be pressed toward each other by finger pressure to grip the hair ends. While these strands are flexible, still they have a greater degree of stiffness than the core and so they serve 20 to afford a firm initial grip on the hair. The device is rotated axially to wind the hair on the roll and the end portions are bent in to hold it in place.

It is to be understood that the invention herein 25 described and claimed may be embodied in various forms and construction.

What I claim is:

1. A hair roll support of the character described comprising a resilient hollow tube of open 30 mesh construction fastened at two spaced points to a non-extensible flexible strand that extends lengthwise through the tube, the strand being free from attachment to or contact with the tube except at the points of fastening. 35

2. A hair roll support of the character described comprising a hollow tube of resilient open mesh braided material tapering towards its end and fastened at its ends to a strand of flexible wire that extends lengthwise through the tube 40 without contacting the latter except at the points of fastening.

3. A hair roll comprising a hollow core member of light stiff resilient material mounted at two fixed spaced points on a flexible strand that extends lengthwise through the core member without contacting the latter except at the points of fastening, and a second flexible strand connected to the first mentioned strand and adapted to lie 45 against the outer surface of the core member. 50

WILLIAM HUPPERT.
